UNITED STATES PATENT OFFICE.

ALBERT GUSTAV HINZKE, OF THUNDER BAY, ONTARIO, CANADA.

SULPHUR BURNER.

1,421,232.

Specification of Letters Patent. Patented June 27, 1922.

Application filed June 17, 1921. Serial No. 478,394.

To all whom it may concern:

Be it known that I, ALBERT GUSTAV HINZKE, a citizen of the United States, and a resident of the city of Port Arthur, in the district of Thunder Bay, in the Province of Ontario, Canada, have invented certain new and useful Improvements in Sulphur Burners, of which the following is the specification.

10 My invention relates to improvements in sulphur burners of a type which is adaptable for use in the paper industry and also in sulphuric acid and fertilizer plants where any grade of sulphur is convertible into SO_2 or any obtainable strength of sulphur dioxide gases, and the object of the invention is:

1st. To devise a burner in which there is no choking of the outlet with sulphur deposits tending to decrease the draught.

2nd. In which the melting kettle is so constructed as to provide greater heat, thereby enabling the sulphur to be melted at the required speed.

25 3rd. In which the sticking of the needle valve due to the uneven expansion and contraction of the parts of the kettle is prevented, in which the needle valve is conveniently located for ready manipulation and is so constructed that it can be readily cleaned out at any time.

4th. In which the clogging of the valve orifice by foreign matter is prevented.

5th. In which the danger to the operator by sulphur ignition during the charging of the kettle with fresh sulphur is obviated.

6th. In which the trays are so constructed and supported as to freely expand and contract to prevent cracking due to the effect of heat and their weight and so that a maximum amount of circulation of the sulphur, air, and gases is effected.

7th. In which the chilling of the furnace by the entrance of fresh air is prevented and in which the gases and air are thoroughly mixed to complete the combustion of the gases.

8th. In which a damper of such a construction is provided that the air supply

50 may be regulated to any degree of fineness. And it consists essentially of the arrangement and construction of parts as herein-after more particularly explained.

Fig. 1 is a vertical sectional view through

Fig. 2 is a sectional view on line 2—2, Fig. 1.

Fig. 3 is a fragmentary enlarged plan detail of a portion of the parts shown in Fig. 2. 60

Fig. 4 is a sectional view on line 4—4, Fig. 1.

Fig. 5 is a sectional view on line 5—5, Fig. 1.

Fig. 6 is a sectional view on line 6—6, 65 Fig. 1.

Fig. 7 is a sectional view on line 7—7, Fig. 1.

Fig. 8 is a detail view in elevation of one of the air supply doors. 70

In the drawings like characters of reference indicate corresponding parts in each figure.

1 is the body or shell of the burner which is composed of a sheet metal wall 2 and a 75 brick lining 3, the bottom being also formed by a sheet metal wall 4 which is riveted or otherwise suitably secured to the wall 2 and is also provided with a brick lining 5. 6 are a series of openings formed in the 80 wall of the shell or body 1 and in each of which is located a door frame 7 provided with a vertically sliding door 8 which is slidably held in side guides 9 formed in the side walls of the door frame. Each door 85 is supported by counterweights 10 connected to the door by metal cords or cables 11 passing over the pulleys 12 which are journaled on suitable studs extending from each door frame 7. 90

By this means the doors 8 may be raised and lowered and held in such raised and lowered position without any further securing means.

13 is a base which is located on the bottom lining 5 of the body 1 of the furnace centrally thereof, and is formed by an annular top portion 14, the central orifice of which is provided with a surrounding groove 15 for a purpose which will hereinafter appear, and by radial walls 16 which rest upon the bottom 5 of the burner so as to provide intervening openings 17 for the passage of the gases, etc. 95

18 and 19 are cylindrical sections which 105 are arranged one upon the other alternately to form a hollow column forming an outlet duct. The lowermost section 18 rests at its lower edge in the groove 15 of the base 13, the top of such section being provided with 110

a similar groove 20 into which the lower portion of the section 19 fits. Similarly each section is built up one upon the other to form the central column aforesaid.

- 5 From each section 18 extends a circular tray 21 the outer edge of the tray being turned up slightly at 22 so that the tray is slightly dished on its upper face. It will be noted that the trays 21 extend into proximity to the interior surface of the shell 1, leaving an annular space 23 for a purpose which will hereinafter appear.

It will also be noted that the outer edges of the trays 21 are slightly below the level 15 of the door openings 6 formed in the shell 1. 24 are trays which extend from each section 19, being formed integral therewith. The trays 24 also extend into proximity to the interior surface of the shell 1, but in 20 this case the annular opening formed there-around is filled with fire clay or other suitable fireproof material as indicated at 25.

The trays 24 are provided with a series of orifices 26 which are arranged around 25 the section 19 as clearly indicated in Fig. 5.

It will also be seen on referring to Fig. 5 that the upper face of the tray 24 is dished, the dished portion extending from its outer edge to between the orifices 26, the upper 30 edge of the orifice being flush with the upper edge of the tray, this portion gradually merging into such upper edge.

27 is a cylindrical member which is disposed vertically resting at its lower end in 35 the annular groove of the uppermost section 19. 28 is my melting kettle. The kettle 28 is divided into two portions 29 and 30, the abutting edges of which are provided with flanges 31 and 32 suitably bolted together.

40 The lower edge of the section 30 of the melting kettle is provided with a flange 33 which rests upon and is secured to the top of the wall of the shell 1. The bottom of the kettle 28 converges downwardly at 34 to the 45 horizontal wall 35 which forms the kettle bottom and which is integral with the cylindrical member 27. 38 are bosses which extend radially from the bottom of the kettle 28 and are provided with needle valve ori- 50 fices 36. 37 is a needle valve provided with a spindle 39 which is threaded into the valve spindle base 40. 41 are orifices which are formed in the top wall of the kettle 28. 42 are feed pipes which extend through the ori- 55 fices 41 and depend downwardly into the kettle, the upper edge of the feed pipe being flush with the upper face of the kettle. 43 are hinged covers forming closures over the orifices 41. 44 is an orifice which is formed 60 in the center of the top of the kettle 28 and from which depends a cylindrical member 45 provided at its lower end with a surrounding groove 46 into which the upper edge of the cylindrical member 27 fits.

65 The member 27 is also provided with an

annular flange 47, the upper face of which is on a level with the upper edge of the downwardly converging portion of the kettle bottom. 48 is a perforated plate which is divided radially into sections 49 as clearly indicated in Fig. 4. The outer edge of each section rests upon the upper portion of the inclined portion 34 of the kettle bottom. The inner edge rests upon the annular flange 47.

49^x is a pipe section provided at its lower 75 end with an outwardly extending flange 50 resting upon the top of the kettle 28 so as to register with the central opening of the cylindrical member 44. The upper end of the pipe 49^x is enlarged at 51 forming a 80 shoulder 52 on which rests a perforated semi-spherical dome 53. 54 is an annular series of port openings located in the pipe 49^x below the shoulder 52. 55 is a similar series of port openings formed above the shoulder 85 52 and also above the perforated dome 53. 56 are rollers which are revolvably carried upon the pipe 49^x to extend radially therefrom below the port openings 54. 57 are similar rollers located below the port open- 90 ings 55.

58 and 59 are rings carried respectively upon the rollers 56 and 57, each ring being provided with openings 60 designed to be carried into and out of a registering position by the handle 61. The upper end of the pipe 49^x is provided with an annular flange 62 to which is secured the flange 63 of an elbow 64.

It will be noted that the elbow 64 is gradually contracted towards its outlet end to which is secured the outlet air discharge pipe 65.

Having described the principal parts involved in my invention I will briefly describe the operation of the same.

In starting the burner, the melting kettle must be filled with sulphur. A shovelful of sulphur must be also thrown through the door opening formed by the door frame 7 and 110 ignited. The sliding doors 8 are then all closed except the two uppermost which are regulated to permit enough air to burn the sulphur freely. When the internal heat has been sufficiently raised to melt the sulphur 115 in the melting kettle one of the needle valves 36 is opened in order to permit the molten sulphur to flow down on the trays as required.

The other needle valve on the opposite 120 side of the machine is a spare one and can be used or not as desired. The melted sulphur and the gases therefrom flow downward from the uppermost tray 24 going inwardly to pass through the orifices 26 125 on to the next succeeding tray 21 flowing again upwardly over the edge of the tray 21 on to the next succeeding tray 24 and then downwardly from tray to tray, the annular stream following a serpentine course 130

until it finally falls upon the brick lining 5 of the bottom of the burner body or shell which acts as the final burning surface for the melted sulphur and indicates the maximum capacity of the burner. From this lowest elevation the gases enter through the openings 17 intervening between the radial walls 16 of the base 13 and through the central opening of the base passing upwardly through the hollow sections 18 and 19 forming a vertical duct together with the cylindrical members 27 and 44 and pipe 50 and passing through the perforated dome 53 into the elbow 60 which finally discharges the gases into the outlet pipe 65 leading to a suitable absorbing system.

All through the sulphur burning process the doors 8 are opened only enough to let the right amount of air into the burner in order to burn the sulphur freely, and as a rule, the upper doors are opened more than the lower doors and it is best to graduate the inflowing air downward to such an extent that the lowermost doors are almost shut.

When the hot gases enter the oxidizing chamber such gases are only partly combusted and oxidized, and it is in this oxidizing chamber formed by the pipe enlargement 51 and the perforated dome 53 that the gases receive their final treatment.

In opening the lower row of port openings 54 which are located beneath the perforated dome 53 enough air is let in, and the air and gas undergo a thorough mixing in passing through the perforated dome causing the final combustion and oxidation of the gases.

The upper row of port openings located above the perforated dome are only opened slightly in order to observe the colour of the flame.

Attention is called to the fact that the inner and outer overflow openings of the trays formed in the one case by the annular series of orifices 26 and in the other case by the annular opening 23, is twice as large as the area of the central duct formed by the sections 18 and 19, sections 27 and 44, and lower portion of the pipe 50 in order to retard the flow of the gases over the burning area and for that reason the outlet under and in the oxidizing chamber is gradually larger than the central chamber in order to let the gases oxidize in an expanded form.

From this description it will be seen that I have devised a burner so constructed as to generate heat sufficient for the proper melting of the sulphur for the reason that all the elements as sulphur, gas, and air pass in the outer chamber from tray to tray downward until they reach the bottom of the burner where the hot gases enter and ascend the inner chamber formed by the central duct thereby providing ample time for the

proper combustion of the gases which during such process of combustion generate heat for melting the sulphur charge, in which the needle valve is so constructed that there will be no danger of sticking as it is carried entirely independent of the melting kettle and is so located as to be easily manipulated and if necessary withdrawn so that the valve orifices may be cleaned out by the insertion of a rod or similar device, in which the danger to the operator is obviated by the employment of the feed pipes 42 which serve to guard the operator from sulphur ignition in filling the kettle with fresh sulphur and which is liable to take place during hot summer weather, in which the trays are so constructed as to be supported independently of the shell or body of the burner and in such a way that they are free to expand and contract particularly in their central portion and such central portion is supported so that when the parts are heated, there is no danger of their cracking due to their weight, in which the gases are thoroughly mixed with the required amount of air before finally leaving the burner so that they are thoroughly ignited and burnt before being finally discharged, in which there is no danger of the supply of fresh air chilling the furnace as it has been previously found when a certain amount of inrushing air follows the inside of the outlet duct having a tendency to lower the temperature, the burning gases forming a central core surrounded by the inflowing air— by my device this air is thoroughly intermixed with the gas so as to produce thorough combustion as hereinbefore referred to—in which I have provided doors which may be readily manipulated so that air may be supplied with any degree of fineness required, and in which the entrance of foreign matter such as stones and pieces of wood passing through the melting kettle into the burner is prevented.

What I claim as my invention is:

1. A sulphur burner comprising a body or shell having an open upper end, a melting kettle provided with feed supply orifices supported upon the open upper end of the shell, valve controlled means for permitting the flow of sulphur from the melting kettle into the shell, a central duct extending through the melting kettle and shell into proximity with the lower end thereof, a discharge pipe leading from the upper end of the central duct and means for causing the flow of molten sulphur as it passes downward to follow a serpentine course to the lower end of the central duct through which the resulting hot gases pass.

2. A sulphur burner comprising a body or shell having an open upper end, a melting kettle provided with feed orifices resting upon the open upper end of the shell, valve

means for controlling the flow of molten sulphur from the melting kettle into the body of the burner, a central duct extending through the melting kettle and downwardly 5 through the body of the burner into proximity to the lower end thereof, a supporting base for the duct provided with radial orifices, and means for directing the flow of molten sulphur as it passes downward in a 10 serpentine course to such radial openings through which the resulting gases pass into the duct and an outlet pipe connected to the upper end of the duct.

3. A sulphur burner comprising a body or 15 shell having an open upper end, a melting kettle provided with feed supply orifices supported upon the open upper end of the shell, valve controlled means for permitting the flow of sulphur from the melting kettle into the shell, a central duct extending through the melting kettle and shell into proximity with the lower end thereof, a discharge pipe leading from the upper end of the central duct, and means for causing the flow of molten sulphur as it passes downward 20 to follow a serpentine course to the lower end of the central duct through which the resulting hot gases pass.

4. A sulphur burner comprising a body or 30 shell having an open upper end, a melting kettle provided with feed supply orifices supported upon the open upper end of the shell, valve controlled means for permitting the flow of sulphur from the melting kettle 35 into the shell, a central duct extending through the melting kettle and shell into proximity with the lower end thereof, and a perforated dome carried within the central duct above the aforesaid ports, a discharge pipe leading from the upper end of the central duct and means for causing the flow of molten sulphur as it passes downward to fol-

low a serpentine course to the lower end of the central duct through which the resulting hot gases pass.

5. A sulphur burner comprising a body or shell having an open upper end, a melting kettle provided with feed supply orifices supported upon the open upper end of the shell, valve controlled means for permitting the flow of sulphur from the melting kettle into the shell, a central duct extending through the melting kettle and shell into proximity with the lower end thereof, a discharge pipe leading from the upper end of the central duct, and means for causing the flow of molten sulphur as it passes downward to follow a serpentine course to the lower end of the central duct through which the resulting hot gases pass.

6. In a sulphur burner, the combination with the burner body, of a melting kettle carried upon the burner body and adapted to discharge molten sulphur into the interior of the burner, a central duct extending through the kettle into the burner, a duct located centrally in the burner and forming an extension of the aforesaid duct and composed of a series of sections abutting one against the other, a supporting base upon which the lowermost section of the aforesaid series rests, such base being provided with radial openings, an imperforate tray extending from each alternate duct section into proximity with the burner wall to leave an annular surrounding opening and a tray having a portion adjacent the centre perforated and extending from the sections alternating with the sections aforesaid and extending at its outer edge into proximity to the wall of the burner and having the space interposed between the edge of such tray and the wall of the burner sealed.

ALBERT GUSTAV HINZKE.
